UNITED STATES PATENT OFFICE.

WALTER H. COTTON, OF CHICAGO, ILLINOIS, ASSIGNOR TO UNION DRAFT GEAR CO.,
A CORPORATION OF ILLINOIS.

DRAFT GEAR.

Application filed May 9, 1924. Serial No. 711,967.

To all whom it may concern:

Be it known that I, WALTER H. COTTON, a citizen of the United States, and resident of Chicago, county of Cook, and State of Illinois, have invented certain new and useful Improvements in Draft Gears, of which the following is a specification, and which are illustrated in the accompanying drawings, forming a part thereof.

10 The improvement relates to draft gears of the friction type, especially designed for use on freight cars.

Its objects are to secure simplicity and compactness of construction, smoothness of 15 action and high efficiency; and a further object is to provide for the delivery of the major portion of the forces to elements under compression, and to relieve such elements as are placed under tension by means 20 of springs, together with a long range of movement of the parts.

A preferred embodiment of the invention is herein shown and described, and in the accompanying drawings—

25 Fig. 1 is a plan section of the gear on the line 1—1 of Fig. 2, as applied to a railway car;

Figs. 2 and 3 are transverse sections on the lines 2—2 and 3—3, respectively, of 30 Fig. 1;

Fig. 4 is a plan view of the gear, partly in section, as applied to a railway car, the gear being under compression; and

Fig. 5 is a sectional view on the line 5—5 35 of Fig. 4.

For the purpose of showing the relation of the gear to a railway car, there is represented a pair of center or draft sills 10; pairs of draft lugs 11, 11, and buffering lugs 40 12, 12, applied thereto; a coupler butt 13; and a coupler extension or yoke 14 for enclosing the gear.

The gear comprises a pair of plate followers 15, 16, which cooperate, respectively, 45 with the draft and buffering lugs and are enclosed within the yoke 14, in accordance with common practice.

A pair of triangular wedge-blocks 17, 17, are seated against the inner face of the follower 15, and a similar pair 18, 18, are seated against the inner face of the follower 16. Preferably, though not necessarily, 50 these wedge-blocks are equilateral, as shown. Each pair of the named wedge-blocks is in-

cluded within a casing 19, 20. These casings being identical in form but one need be described.

The casing, as 19, is open at both ends. The inner faces of the portions of its side walls which are adjacent to the follower 15 flare outwardly, as shown at 21, at an angle corresponding to that of the adjacent faces of the blocks 17, with which they engage. The remaining portions of the inner faces of the side walls of the casing are inclined 65 outwardly, as shown at 22, toward the opposite end of the casing, providing wedging surfaces for engagement by correspondingly inclined portions of a pair of wedge plates 23, 24, which constitute seats for a spring 70 or pair of nested springs 25, disposed transversely to the axis of the gear.

A central wedging element and spring guide 26, arranged on the longitudinal axis of the gear, has its ends beveled to constitute double faced wedges 27, 27, which are interposed, respectively, between and cooperate with the wedge-blocks 17, 17, and 18, 18. The member 26 is transversely apertured to receive the spring 25 and hold it so against lateral displacement, permitting its free compressive movement.

The members 19, 20, constitute wedging elements which cooperate not only with the triangular blocks but also with the elements 23, 24. They also constitute casings 85 for inclosing these elements, and they are placed under tension by the action thereof.

Preferably guide ribs, as 28, are formed on the inner faces of the top and bottom 90 walls of the members 19, 20, and engage corresponding channels in the member 26, serving to prevent any tendency of the latter to get out of normal position.

At the side margins of the wedge faces 95 22 of each of the casings 19, 20, there are instanding flanges 29 between which the wedge-shaped portions of the plates 23, 24, slide and are guided.

In action the follower to which pressure 100 is applied through the coupler is moved away from the sill lugs with which it cooperates, carrying with it the triangular wedge-blocks, against the resistance of the spring 25 and the resistance to movement of 105 the member 26 by the triangular wedge-blocks at the opposite end of the gear. The member 26 forces the triangular blocks of

both pair apart as the compression of the gear continues, and the outward movement of these blocks forces the elements 19, 20, away from the followers with which they 5 are associated, and by reason of their wedging engagement with the elements 23, 24, cause the compression of the spring 25. The triangular wedge-blocks are placed under compression and, with the member 26, carry the 10 major portion of the load.

While the elements 19, 20, are subject to tensional or bursting stresses, they are relieved from much of the duty of resisting the shocks of service by the yielding of the 15 spring 25, and the burden put upon them is not localized because of the comparatively long range of their movement relative to the members 23, 24.

The release of the gear is effected by the 20 spring 25, the members 19, 20, being moved backwardly to normal position by the wedging action of the elements 23, 24, the remaining parts of the gear being also restored to normal position by this action.

25 The gear possesses the advantage of simplicity both as to the form of its parts and the ease with which they may be manufactured, no machinery being necessary. It is compact and easy of assembling. Its efficiency is high due to the large number of frictional surfaces in cooperation. Furthermore, it so distributes the stresses incident to its compression that the major part thereof 30 is resisted by parts which are under compression, and for this reason the parts which are placed under tension may be made comparatively light without danger of fracture.

The form of construction shown and 35 described is, as now advised, the most desirable, but does not constitute the essence of the 40

invention, the scope of which is sufficient to include other forms.

I claim as my invention—

1. In a draft gear, in combination, a pair 45 of followers, a pair of triangular wedge-blocks seated against each follower, a member having wedge-shaped ends each engaging adjacent faces of one pair of blocks, a spring extending transversely through such member, a spring seat applied to each end of 50 the spring and having wedging faces, and a casing inclosing each pair of blocks and having wedging faces cooperating with the outer faces of the blocks, and wedging faces cooperating with wedging faces of the 55 spring seats.

2. In a draft gear, in combination, a longitudinal member having wedge-shaped ends and provided with a transverse aperture for housing and guiding a spring, a spring 60 within the aperture, spring seats applied to the ends of the spring and having wedge faces, and wedging elements cooperating with the wedges of the first-named member and with the spring seats. 65

3. In a draft gear, in combination, a longitudinal member having wedge-shaped ends and provided with a transverse aperture for housing and guiding a spring, a spring 70 within the aperture, spring seats applied to the ends of the spring and having wedge faces, a pair of triangular wedge-blocks cooperating with each end of the first-named member, and a pair of casings inclosing the 75 named elements and having internal wedging faces cooperating with the wedge faces of the spring seats and the triangular blocks and guide ribs engaging the first-named member.

WALTER H. COTTON.
